[57] CLAIM

The ornamental design for a shower head, as shown and described.

DESCRIPTION

FIG. 1 is a perspective view of a shower head showing my new design;

FIG. 2 is a side elevational view thereof, the opposite side being identical except for the lack of a middle flange, the two side flanges placed closer, and the lack of two small outlets;

FIG. 3 is a bottom plan view thereof; and

FIG. 4 is a top plan view thereof.

The broken line drawing is shown for illustrative purposes only and form no part of the claimed design.
